PACKING FOR PISTON-RODS.

1,128,123.

Specification of Letters Patent.

Patented Feb. 9, 1915.

Application filed June 9, 1911. Serial No. 632,240.

To all whom it may concern:

Be it known that I, FRANKLIN WM. FRITCHIEY, a citizen of the United States, residing at Sandusky, in the county of Erie and State of Ohio, have invented a new and useful Improvement in Packing for Piston-Rods, of which the following is a specification.

My invention relates to certain improvements in packing for pump piston rods, locomotive throttle rods, locomotive, marine, and stationary engine piston rods, valve stems, and for other reciprocating rods, and consists in a combination packing, composed of a soft or fibrous element in conjunction with a metallic or Babbitt ring, the one supplementing the other and serving to overcome the difficulties in satisfactorily packing piston rods, and other reciprocating rods.

Figure 1 is a sectional view of my improvement as applied to a locomotive throttle rod stuffing box. Fig. 2, is a perspective view of one half of one of the Babbitt rings as used in the ordinary stuffing box, as shown in Figs. 1 and 3. Fig. 3, a sectional view as applied to a locomotive air pump piston rod stuffing box. Fig. 4, is a perspective view of one half of one of the Babbitt rings as used in the arrangement as shown in Figs. 7 and 8 having a more acute angle, or longer taper, on the one end over which is fitted the follower ring which in turn is acted upon by the pressure of the coil spring and steam pressure. Fig. 5, end view of the two parts of my Babbitt rings. Fig. 6, side view of the two parts of same, showing the beveled ends and overlapping joints. Fig. 7, is a sectional view of my device applied to a locomotive valve stem. Fig. 8, is a sectional view of my device applied to a locomotive piston rod.

My invention consists of a metallic or Babbitt metal ring B, and a fibrous ring A, interposed between it and the outer end of the stuffing box D, and in the construction and arrangement of the parts.

The metallic ring comprises two semi-annular members, each having one of its ends constructed as complementary in form to its other end, so that when two such members, rotated 180° to each other without inverting them, are brought into abutment, they fit together and complete the ring. Hence, the ring is made up of two geometrically identical pieces and its production and handling involve merely a single character-

istic piece of metal multiplied appropriately to the demand for its use; and these pieces are readily removable, and reversible in position; the sides being interchangeable either singly or in pairs. The ring is constructed with a cylindrical inner surface and an outer surface that is conical at the ends and cylindrical between the ends, and to adapt the ends to fit together with the advantages hereinafter recited, each semi-annular member is constructed at one end with a rhomboidal projection and a triangular recess, and at its other end with a rhomboidal recess and a triangular projection; these projections and recesses being formed to provide between each two abutting ends of said members, one pair of faces abutting in the direction of the axis of the ring, and two pairs of faces abutting in the direction of its circumference; the circumferential abutments at each end of each member being in two circumferentially offset planes substantially parallel to a radius of the ring intermediate of said planes, whereby a joint is produced that is overlapped against escape of fluid in the axial direction, and these abutting faces together equal the entire sectional area of the ring; and each axial abutment being confined within the zone of the outer cylindrical portion of the ring and being in a plane that is perpendicular to the planes of the circumferential abutments but inclined to both the radius and axis of the ring; these axially abutting faces at the respective ends of a single member being also inclined to each other, so that when the halves of the ring are pressed together axially, there is no tendency to spread either ring relatively to the other, but each ring is left free to be compressed upon the rod. This construction of abutting ends of the ring segments is productive of a number of advantages. The joints are sealed against direct passage both radially and axially; the segments assemble by true diametric movements instead of by combined diametric and axial movements, as in ring segments having longitudinal abutment in planes inclined to the offset planes and, therefore, require less room in an axial direction for the insertion of the ring, and avoid circumferential spreading tendency under axial pressure of the packing gland or follower. In the preferred construction, the segments have the further characteristics of being not

merely symmetrical, but identical in form, so that two segments made in the same mold will fit together when presented to each other in reversed positions, thus not only 5 simplifying manufacture, but avoiding the inconvenience and expense of keeping two kinds of ring segments.

As will be seen from the drawing, the 10 ring embodies an intermediate cylindrical portion and conical end portions. The joint on one side has the inclined axial abutting plane parallel to one conical end, and the inclined axial abutting plane of the other joint is parallel to the other conical end. 15 Incident to this condition is the fact that the inclined axial abutment planes on opposite sides of the ring are at different but symmetrical angles to the axis, so that when the ring is in position on a rod which it fits, 20 the members abut in one axial direction on one side and in the opposite axial direction on the other side, so that there can be no relative axial displacement between the segments. The inclined axial abutting planes, 25 while substantially perpendicular to the offset circumferential abutting planes, may, if desired, be slightly undercut to produce a slight interlock, though not sufficiently undercut to defeat the advantage of having 30 them essentially perpendicular to said offset planes.

The metallic ring is made in two parts as shown in Figs. 2, 4, 5, and 6, with overlapping lips K, K, L, L, and is of cone shape 35 on each of its ends, the cone or bevel being made to such angle as will suit the conditions to be met in actual use. For use with the ordinary stuffing box type, and where access to the adjustments of the gland can 40 be had, the angle or bevel is made 45 degrees at both ends. For use with the locomotive piston and valve stem, which depend upon the pressure of steam and a coil spring for adjustment, the angle of the bevel on 45 the pressure end is ordinarily 67 degrees, the opposite end retaining the ordinary 45 degree angle, the 67 degree angle giving more bearing surface for the steam, and the follower ring hugs the longer angle better 50 than that of 45 degrees.

My Babbitt ring is made with overlapping lips at the joint, as shown in Figs. 2, 4, 5, and 6, to prevent the escape of steam, and to provide means for taking up wear 55 of the ring. The overlapping lips of the ring are made, ordinarily, at the same angle as that of the beveled ends, and as pressure is exerted against the outside bevel ends these angles all tend to close the ring to the 60 rod, and at the same time the lap joints are kept pressure tight. The end of my fibrous ring that rests against the end of the cup, is made to conform to the inside end of the cup, while the end next to the Babbitt ring 65 is funnel shaped to fit snugly against the

bevel end of this ring. The angular bearing of these two rings, the one against and partially within the other, tends to force or wedge the fibrous ring out to fit the bore of the cup making the cup pressure tight, and at the same time forces the Babbitt ring tight against the rod to prevent leakage. 70

Should the Babbitt ring, with long usage, wear loose up on the rod, the two parts can be taken out and the ends of the overlapping lips be filed off a little, when they will fit as before. The overlap joint lips are so constructed that the contact faces are on about the same angle as the outer bevel, and between the beveled ends is the ring proper, 75 that fits loosely against the walls of the vibrating cup. The split between the two halves of the metallic ring extends, on one side, longitudinally, through the beveled end and across the annular part, thence at right angles between the edge of this and the other beveled end and thence at right angles out through the other beveled part. This latter beveled end, in practice, is placed against the fibrous packing, so that the splits 80 of the overlap joints of both halves of the ring, embed in the fibrous packing, become pressure tight, and prevent the leakage at the overlap joints. 90

The objections to the use of fibrous packings solely, are that the wear is rapid, the packing is short lived and becomes expensive, and the trouble of repacking troublesome. With the use of metallic packing, alone, it is necessary to fit the same accurately to wedge shaped cups to insure to some degree against a non-leaking condition, both at the rod-fit and over the outside of the packing. This is also an expensive and troublesome packing, as it wears and tends to lose its efficiency as a pressure tight 100 fit, and its outer accurate fit to the cup, especially in air pump piston rod stuffing boxes, where it requires special fixtures and the dissembling of the pump to apply or 105 change the same. 110

In my arrangements the metallic rings can be molded and used without machining or fitting of any sort, the Babbitt ring embedding itself in the fibrous ring, the latter 115 adjusting itself to any irregularities in the surface of the ring.

In the ordinary stuffing box, as in the air pump, the Babbitt ring can be applied with a fibrous ring on each side or end, and the gland be forced against this packing with just enough pressure to stop leakage, and as only a slight pressure is required, no excessive wear to the Babbitt ring will be experienced. 120

In the locomotive throttle rod stuffing box I sometimes use an extra brass ring I, although this is not essential, the fibrous packing being used at both ends of the Babbitt ring, the brass follower ring having a ta- 125 130

pered bore to fit the longer taper of the Babbitt ring, on the pressure side.

What I claim is:

1. A ring for rod packings; said ring having its interior surface cylindrical and its exterior surface formed with conical ends and a cylindrical intermediate portion; said ring comprising two geometrically identical segments abutting together both in the direction of the circumference of the ring and in the direction of its axis; each circumferential abutment being in two offset planes substantially parallel to radii of the ring and corresponding in area to the transverse section of the ring, and each axial abutment confined within the outer cylindrical zone of the ring, and being in a plane substantially perpendicular to the adjacent offset planes, but inclined to the axis of the ring; said inclined axial abutment planes being at the same inclination to the axis as the respective conical ends of the ring.

2. A metal packing ring having a cylindrical inner surface and an outer surface that is conical at the ends and cylindrical between the ends; said ring comprising two

geometrically identical semi-annular members, each constructed at one end with a rhomboidal projection and a triangular recess, and at its opposite end with a rhomboidal recess and triangular projection; said projections and recesses providing between each two abutting ends of said members, one pair of faces abutting in the direction of the ring's axis, and two pairs of faces abutting in the direction of its circumference; the circumferential abutment at each end of each member being in two circumferentially offset planes substantially parallel to a radius of the ring intermediate of said planes and together corresponding to the entire sectional area of the ring; and each axial abutment being confined within the zone of the outer cylindrical portion of the ring and being in a plane that is perpendicular to the planes of the circumferential abutments, but inclined to both the radius and axis of the ring.
